UNITED STATES PATENT OFFICE.

MARTHA B. ORRICK, OF BALTIMORE, MARYLAND.

DESIGN FOR A CARD HOLDER.

Application filed November 12, 1921. Serial No. 514,797. Term of patent 7 years.

To all whom it may concern:

Be it known that I, MARTHA B. ORRICK, a citizen of the United States, residing at Baltimore, in the State of Maryland, have invented a new, original, and ornamental Design for Card Holders, of which the following is a specification, reference being had to the accompanying drawing, forming a part hereof.

In the drawings:—

I claim:—

The ornamental design for a card holder as shown.

In testimony whereof, I affix my signature.

MARTHA B. ORRICK.
